COMBINED DISPLAY CARTON AND EASEL ASSEMBLY

Patrick A. Toensmeier, Hamden, Conn., assignor to The New Haven Board & Carton Company, New Haven, Conn., a corporation of Delaware

Application February 24, 1956, Serial No. 567,616

2 Claims. (Cl. 206—45.27)

This invention relates to cartons of the type used in both the shipment and display of merchandise and is concerned more particularly with a novel carton having an attached easel for supporting the carton in such a position that the contents thereof and advertising matter printed thereon are effectively displayed. Parts of the easel may be folded to lie against the walls of the carton and thereby provide extra thickness of material, which afford additional protection for the contents of the carton, and, when the carton is used for shipping fragile articles, such additional protection is highly desirable. At the point of use, the easel may be quickly set up into operative position.

The carton and easel are made of paperboard and are formed from separate blanks secured together by gluing. Since the blanks are separate, they may be made of different materials, and this is advantageous, in that the easel blank may be made of a material not suitable for the carton but desirable for the easel because of its strength, low cost, etc. Also, the easel blank may be cut from the board, of which it is formed, in such manner that, in the easel blank, as applied to the carton blank, the grain of the material runs in a direction giving the maximum strength and stiffness to supporting members of the easel. This makes it possible to obtain such qualities in an easel made of less expensive board than would otherwise be required.

For a better understanding of the invention, reference may be made to the accompanying drawing, in which:

Fig. 1 is a perspective view of the new carton and easel assembly with the easel collapsed;

Fig. 2 is a perspective view of the assembly of Fig. 1 with parts broken away and with the easel in operative position; and

Fig. 3 is a plan view showing the blanks from which the carton and easel are formed.

The carton of the new assembly is made from a blank 10 of paperboard or similar material, which comprises a bottom wall 11, side walls 12, 13, pairs of end wall flaps 14, 15, and end walls 16, 17. The side and end walls 12, 13 and 16, 17 are hinged to the side and end edges of the bottom wall 11 along crease lines, and the end wall flaps 14, 15 are hinged to the opposite ends of side walls 12, 13 along crease lines. The flaps 14, 15 have tabs 14a, 15a at their free ends, which may be interlocked to connect the flaps of each pair together to form the outer wall of a double end wall.

The end wall 16 is hinged to one end edge of the bottom wall 11 along a crease line and is adapted to be folded at right angles to the bottom 11 to lie inside the interlocked end flaps 15 and form the inner wall of the double end wall at that end of the carton. A similar end wall 17 is hinged at the opposite end of the bottom wall 11 and is arranged to lie inside interlocked flaps 14 to form the inner end wall at that end of the carton.

A cover 18 is hinged along the free edge of the end wall 17 and is of a size to close the carton. The cover is provided along its side and end edges with tuck flaps

2

19 and 20 connected to the cover along crease lines. A scored line 21 in the cover 18 near its root end divides the cover into two portions. The portion of the cover between the scored line 21 and the end wall 17 may be used as a display flap and, for that purpose, carries advertising matter or the like.

The bottom wall 11 is provided along its side edges with short U-shaped cuts 22 terminating at the crease lines between the bottom wall and side walls 12, 13, and the cuts form tongues 23 at the lower edges of the side walls.

The easel is formed from a blank 24 which may be of material different in its characteristics from the material used in the carton blank 10. The easel blank 24 comprises a support 25, which is of a width at least equal to and preferably slightly greater than that of the bottom wall 11 of the carton, and the length of the support 25 is somewhat less than the length of the bottom wall. A glue flap 26 is attached to the support 25 at its upper end along a crease line 27, which provides a hinge connection between the support and the glue flap. A pair of triangular tie flaps 28 are connected to opposite side edges of the support along crease lines 29 and the altitude of the flaps is substantially equal to the width of the carton side walls 12, 13. Each tie flap 28 has a connecting tongue 30 projecting outwardly from one edge, and, as shown in Fig. 3, the tongues are positioned on the edges of the flaps adjacent the glue flap 26. The edges carrying the tongues may be considered the upper edges of the flaps. A foot flap 31 is secured to the bottom edge of the easel support member 25 along a crease line 32 and the foot may be bent out of the plane of the support 25 to engage the surface, upon which the carton rests, and impart rigidity to the support.

The easel blank 24 is attached to the carton by gluing the flap 26 to the bottom wall 11 near one end thereof. The supporting member 25 is centered with respect to the side edges of the bottom wall 11, so that the tie flaps 28 may be folded to overlie the side walls 12, 13 of the carton and extend to the free edges thereof. As thus assembled, the carton and easel blanks lie flat and may be conveniently shipped from the point of manufacture to the point at which the cartons are to be filled.

To erect the carton, the side walls 12, 13 and end walls 16, 17 are bent at right angles to the bottom wall 11, after which the pairs of end wall flaps 14, 15 are bent inwardly, toward each other, at right angles to the side walls 12, 13 and locked together to form the outer walls of the double end walls. The tie flaps 28 are then bent to lie against the side walls 12, 13 of the carton and, in this condition, the carton is ready for filling. After filling, the cover 18 is closed with the tuck flaps 19, 20 bent at right angles to the cover and inserted into the carton to lie against the inner surfaces of the side walls 12, 13 and the end tuck flap 20 inserted between the end wall 16 and the interlocked flaps 15.

When the carton is filled and ready to be shipped, the support 25 and flaps 26 and 31 lie in a single plane against the outer surface of the bottom wall 11 and the tie flaps 28 lie at right angles to the support 25 and against the side walls 12, 13 of the carton. With the carton in this condition, double thicknesses of paperboard material are provided along the bottom wall of the carton and along the center portions of its side walls. The provision of the additional thicknesses of material on the bottom and side walls of the carton is advantageous and highly desirable for shipping fragile articles, such as cookies, for example, since the carton is more resistant to crushing.

At the point of use, the carton assembly may be set up for display by drawing the lower end of the easel

support 25 away from the bottom wall 11 of the carton until the inner edges of the tie flaps 28 are aligned with the bottom wall 11. The connecting tongues 30 on the flaps are then inserted into the slots 23 to lock the easel in its operative position and the foot flap 32 is folded out of the plane of the support 25 to lie flat on the counter or other supporting surface, on which the carton is to be set up. The flap 32 may be folded outwardly, as shown in Fig. 2, or inwardly, whichever is desired. In either case, the flap 30 prevents the lower edge of the support 22 from buckling transversely.

When the carton is set up for display, the free end portion of the cover 18 beyond the scored line 21, is torn away to expose the interior of the carton. The remaining portion of the cover remains and forms a display flap, as indicated in Fig. 2.

The new carton has important advantages over similar prior cartons, in that the easel member may be collapsed against the side and bottom walls of the carton, imparting substantial additional strength thereto to resist forces normally encountered during shipping. Since the easel blank is separate from the carton blank, it may be made of a different material selected for its desirable characteristics, and it is possible to orient the grain direction of the easel member in such manner that the maximum strength is derived from the material used.

I claim:

1. A combined display carton and easel assembly which comprises a carton having a bottom wall and side walls connected to the side edges of the bottom wall along hinge lines, the hinge lines having openings spaced from their ends, and an easel separate from the carton

and having a glue flap at one end secured to the bottom wall of the carton near one end thereof and extending transversely of the wall, a support at least as wide as the bottom wall secured to the glue flap at one end for swinging movement about an axis lengthwise of the flap from a position in contact with the bottom wall to a position at an angle thereto, the other end of the support being free, and triangular tie flaps hinged to the side edges of the support and of an altitude substantially equal to the width of the side walls of the carton, the tie flaps being adapted to lie in contact with the outer faces of said side walls with the apices of the flaps lying close to the median line across the carton side walls, the tie flaps having free edges engageable with the bottom wall of the carton to hold the support at an angle to that wall and tongues projecting from their edges and receivable in the openings in the hinge lines of the carton to retain the easel in erected condition.

2. The assembly of claim 1, in which a foot flap is hinged to the free edge of the support and adapted to be folded at an angle to the support to strengthen the support against transverse buckling.
